(No Model.)

A. S. EVANS.

INVALID BEDSTEAD.

No. 257,483.

Patented May 9, 1882.

UNITED STATES PATENT OFFICE.

ANNIE S. EVANS, OF KINGSTON, ONTARIO, CANADA.

INVALID-BEDSTEAD.

SPECIFICATION forming part of Letters Patent No. 257,483, dated May 9, 1882.

Application filed September 16, 1881. (No model.)

To all whom it may concern:

Be it known that I, ANNIE S. EVANS, of Kingston, Province of Ontario, Canada, have invented a new and Improved Adjustable 5 Couch for Invalids, of which the following is a full, clear, and exact specification.

The object of my invention is the production of an inexpensive couch, bed, or chair adapted to be placed upon ordinary bedsteads, by means 10 of which sick and infirm persons may be easily and comfortably raised and supported in different postures, the device having such construction that it may be folded into small compass for convenience in transportation and 15 stowing away when not in use.

My invention consists principally of a divided and hinged hammock-like couch, bed, or chair-bottom placed upon hinged knees, the lower ends of which knees rest upon and are 20 hinged to the main base or side boards, the hammock-like bottom being adapted to be raised or lowered, to suit the desire of the patient, by means of straps passing over a winding-drum.

25 The invention also consists in the combination, with the hammock-like bottom, supported and adapted to be operated as just described, of an elevated table or leaf at the foot of the device; and, also, of the details of construction and of the arrangement and combinations 30 of parts, as hereinafter described, and pointed out in the claims.

Reference is to be had to the accompanying drawings, forming part of this specification, 35 in which similar letters of reference indicate corresponding parts in all the figures.

Figure 1 is a side elevation of my invention. Fig. 2 is a plan view of the same, with a part of the table broken away to clearly show the 40 winding-drum. Fig. 3 is a side elevation, showing the bed-bottom let down for supporting the patient in a horizontal position. Figs. 4, 5, and 6 are detailed views, showing a modified form of the bed-bottom, and Fig. 7 is a 45 perspective view of one of the knees removed from the device.

In the drawings, A represents the hammock-like couch, bed, or chair-bottom, upon which the patient sits or lies, and B B represent the 50 base or side boards, upon which the bottom A is supported by means of the knee-pieces C C

and C', which are hinged at their upper ends to the under side of the side bars, a a and a', which form the hinged sections K K' of the hammock-like bottom, and at their lower 55 ends to the upper side of the base-boards B B, the hinges being on opposite sides of the knee-pieces, as shown. These knee-pieces C C and C' are set transversely upon the boards B B, and they are made wider at the bottom than 60 at the top, so as to act as braces to prevent the bars a and a' tipping inwardly from the weight of the person on the cross-pieces or straps e e, which form the support for the person; and the knee-pieces C', at the head of 65 the couch, bed, or chair-bottom, may be longer than the knee-pieces C C, as shown in Fig. 1, or they may be of about the same length and made extensible, as shown clearly in Fig. 6, for elevating and inclining section K' of the 70 bottom higher than the chair-section K when the hammock-like bottom is raised from the position shown in Fig. 3 (which shows the knees folded back upon the base-boards B B to make the bottom horizontal for supporting 75 the patient incumbently) to that shown in Fig. 1, for use as a chair or reclining-couch, the hinges e e permitting this elevation and inclination of the said section.

For easily raising and lowering the bed or 80 chair-bottom A without jarring or otherwise inconveniencing the patient, I provide the device with the winding axle or drum E, over which the straps or connections b b, which are connected to the rear ends of the bars a a, pass. 85 This axle or drum is journaled in the vertical side boards, F F, and is provided at one end of its journal or shaft with the large cog-wheel g, into which meshes the pinion g', which is fixed upon the crank-shaft i. The outer face 90 of the large cog-wheel is provided with the ratchet j, with which the pawl J engages for preventing accidental backward movement of the drum.

If the plain or non-extensible knees C' shown 95 in Fig. 1 are to be used, I hinge upon the upper side of the bars a' a' the auxiliary frame or support D, which forms the back when the device is to be used as a chair, and which may be adjusted to different angles or inclinations, 100 to suit the patient, by means of the braces d' d', hinged to the bars d d, composing the aux-

iliary frame, the lower ends of which braces are adapted to engage with the notches $f f'$, made in the upper sides of the bars $a' a'$. The outer ends of bars $d' d'$ are tied together by the tie-rod k , as shown in Fig. 2. In this construction the auxiliary frame is made to carry the cross-straps $c c$; but if the extensible knee shown in Fig. 4 is to be used this frame D is dispensed with, and the cross-straps $c c$ are carried by the side bars $a' a'$. The extensible knees are formed by making the longitudinal slots c' in the knee-pieces C' and providing the same with the notched bar H , which is provided with the headed studs $n n$, which move in the slots c' , the upper end of the notched plates being provided with the upper hinges, the knee-pieces being provided in the proper place with the spring-actuated pawl or dog N , which engages with the notches of the plate H as it is raised or lowered to adjust the section K' , and serves to support the section at any inclination for holding the patient in a sitting, reclining, semi-reclining, or incum-
bent position, as desired.

25 In order to support the limbs of the patient in different positions for greater comfort and rest, I provide the bars $a a$ of the seat-section K with the adjustable hinged frame E', which is composed of the bars $h h$ and the hinged
30 braces $h' h'$, the lower ends of which are adapted to engage with the notches $f' f'$ in the upper sides of the bars $a a$, as shown in dotted lines in Fig. 1. When this frame is used the cross-straps $c c$ are attached to the bars $h h$; but when it is not used the said cross-straps are attached to the bars $a a$, as shown in Fig. 4.

Upon the top of the upright side pieces F F is placed the board G, to which is hinged the leaf I, which may be turned out, so as to be
40 in convenient position in front of the patient when used as shown in full lines in Fig. 1; or tipped back upon the board G out of the way when not in use, as shown in dotted lines in the said figure.

45 It will be observed that in raising the couch, bed, or chair-bottom from the position shown in Fig. 3 to that shown in Fig. 1, where the

knees C C and C' stand vertical, the patient will be carried forward near to and partly under the table, thus rendering the table particularly convenient and serviceable. 50

The vertical side boards F F are made wider at the bottom than at the top, as shown in the drawings, to act as braces to lessen the strain at the point where they stand upon the side boards B B. 55

A very thin mattress may be made to accompany my invention, if desired.

Having thus fully described my invention, I claim as new and desire to secure by Letters Patent—

1. In an invalid-couch, the combination, with the base B and the side bars of the hinged sections K K', of the knees C C', hinged to the said side bars and base, substantially as 65 and for the purpose set forth.

2. In an invalid-couch, the combination, with the base B, the winding drum E, and the cord or strap b, of the hinged sections K K' and the knees C C', hinged to the side bars of the 70 said sections and to the base, substantially as and for the purpose set forth.

3. In an invalid-couch, the combination, with the side bars, a a', of the hinged sections K, provided with notches f', of the hinged foot- 75 rest E' and the braces h', hinged to the end of the side bars of the said foot-rest, substantially as and for the purpose set forth.

4. In an invalid-couch, the combination, with the base B and the hinged section K', of the 80 knees C', hinged to the base and provided with the adjustable sliding bar H, hinged to the said section, substantially as and for the purpose set forth.

5. In an invalid-couch, the combination, with 85 the base B and the hinged section K', of the knee C', provided with the slot c', and the spring-dog N, and the notched bar H, provided with the headed studs n, substantially as and for the purpose set forth.

ANNIE SOPHIA EVANS.
